UNITED STATES PATENT OFFICE

THEODOR ZETTERLUND, OF MILWAUKEE, WISCONSIN, ASSIGNOR TO KERNER AUTOMATIC HOIST CO., OF MILWAUKEE, WISCONSIN

HOISTING MECHANISM

Substitute for application Serial No. 150,716, filed November 26, 1926. This application filed January 19, 1931. Serial No. 509,782.

This invention relates to a hoisting mechanism, and is a substitute for application Serial No. 150,716, filed Nov. 26, 1926.

Objects of this invention are to provide a novel form of hoisting mechanism, such for example, as that employed in operating temporary elevators used in construction work, which is so constructed that a worm and worm wheel are interposed in the driving gear train for the hoisting mechanism with the worm and worm wheel having a locking relation, so that the worm can not be driven backwards by the load imposed on the hoisting mechanism, and to provide means for selectively coupling either of two reversely rotating members to the worm, such control mechanism permitting the coupling of only one of such members at a time.

Further objects are to provide a hoisting mechanism in which a locking worm and worm wheel are employed, and in which quick motion mechanism is provided for positively locking either of two reversely rotating members to the worm shaft, so that there is no slipping engagement as the members lock the rotating members in operative connection with the shaft, but in which such locking is quickly and positively secured.

Further objects are to provide a compact, serviceable and novel type of hoisting mechanism in which the entire apparatus is portable and self-contained, and in which the worm is rotated in either direction by means of loosely mounted clutch controlled pinions which mesh with a main driving gear, such gear being in turn driven by a pinion.

An embodiment of the invention is shown in the accompanying drawings in which:

Figure 1 is a side elevation of the apparatus;

Figure 2 is a sectional view on the line 2—2 of Figure 1;

Figure 3 is a sectional view on the line 3—3 of Figure 1;

Figure 4 is an end view of the apparatus with one of the end caps of the main casing removed;

Figure 5 is a fragmentary view to an enlarged scale similar to Figure 1, taken from

the opposite side with the hoisting drum removed.

Referring to the drawings, it will be seen that the apparatus comprises a base or frame work 1 which carries the driving motor 2, and the hoisting mechanism, hereinafter described. This frame may be carried by a plurality of small rollers 3 so that it may be easily drawn or pushed into position and may be readily transported.

The motor is provided with a driving shaft 4 which is coupled by means of the universal joint 5 to an aligned shaft 6. This shaft 6, as may be seen from Figure 2, carries a bevel pinion 7 which meshes with a bevel gear 8. This bevel gear is provided with a double face, as may be seen from Figure 2, and its inner face meshes with a pair of bevelled pinions 9, and, consequently, reversely rotates such pinions. These pinions are loosely mounted upon a worm shaft 10, such shaft being rigidly keyed to a worm 11. Suitable ball bearings are provided, as shown in Figure 2, to reduce the friction of the parts.

It is to be noted from Figure 2 that each of the bevelled pinions 9 is provided with a clutch having dog teeth 12 and that a pair of slidable clutch members 12 are loosely splined to the shaft 10. These clutch members 12 also have dog teeth 13 which are adapted to positively interlock with the teeth 12' when the clutches are closed. These clutches are controlled by the forked levers 14 which, as may be seen from Figure 5, are carried by shafts 15. These shafts 15 project outwardly from the main casing 16, which houses the worm, the pinions, and the bevel gear and clutch parts, as previously described, and consequently which may carry a lubricant and be sealed against loss of such lubricant. The shafts 15 carry inwardly projecting levers 16' which are provided at their free ends with rollers or cam followers 17. These cam followers are adapted to ride upon a cam disc 18. It is to be noted that the disc 18 is provided with a notch or cutout 19 into which one or the other of the rollers 17 may snap. It is to be noted further that the levers 16' are urged into clutch closing position by means of the tension springs 20. Further, it

is to be noted that the levers 16' are each provided with projecting lugs 21 which are normally locked to hold the levers 16 against upward motion by means of lugs 22 carried by 5 latching levers 23. These latching levers 23 are provided with stops 24 and are held in latching position under normal conditions by means of the spring 25, which, as may be seen from Figure 5, extends from one of the levers 10 23 to the other.

The cam disc 18 is integrally formed with a projecting ear or lug 26 which constitutes a trip and is adapted to strike the projections 22 and to thus unlock the corresponding latch 15 23 and permit the appropriate levers 16' to snap inwardly with a quick motion, as the notch 19 is then positioned opposite the corresponding roller 17. This causes the corresponding clutch to quickly close and to positively lock its pinion to the worm shaft. There is no friction slip in this mechanism, but instead the pinions are quickly and positively locked alternately to the shaft in accordance with the rotation of the controlling 20 cam disc 18. This cam disc 18 is mounted concentrically with the hoisting shaft 27, and is provided with a controlling lever 28 integral therewith and apertured, as shown in Figure 5, for the reception of a control link 25 or control cables. Obviously, the control cables may extend along the elevator shaft and may be connected to limit mechanism actuated by the elevators.

The shaft 27 carries a worm wheel 20 (see 30 Figure 3) which has an interlocking engagement with the worm 11, so that when the worm ceases to rotate the shaft 27 is locked against motion.

The shaft 27 carries at its outer end a hoisting drum 30 which receives the hoisting cables in the usual manner.

In order to hold the cam disc 18 in neutral position against inadvertent rocking motion, a roller 31 (see Figure 5) is provided. This 45 roller normally seats within the notch 19 and thus holds the cam disc against rotary motion. The roller is carried by a spring pressed plunger 34 (see Figure 3) which is guided in the main casing of the machine.

50 It will be seen, therefore, that a very simple and serviceable type of hoisting mechanism has been provided by this invention, which permits the selective engagement of the worm shaft with either of the two reversely rotating pinions. Further, it will be seen that the reversely rotating pinions are driven in a simple manner by a bevel gear, and that this bevel gear in turn is driven by a pinion operatively connected to the motor shaft.

60 It will be seen further that the entire apparatus is of rugged and substantial construction and is foolproof.

Although the invention has been described in considerable detail, such description is intended as illustrative rather than limiting as

the invention may be variously embodied and as the scope of such invention is to be determined as claimed.

I claim:

1. In a hoisting mechanism, the combination of a driven shaft, a worm wheel mounted upon said shaft, a worm having a locking engagement with said worm wheel and having an extended shaft, a pair of pinions carried by the worm shaft and loosely mounted thereon, clutches for positively locking said pinions to said shaft, a bevel gear for rotating said pinions in opposite direction, a pair of levers for operating said clutches, springs urging said levers into clutch closing position, a cam disc cooperating with the free end of said levers and having a notch permitting one or the other of said levers to move inwardly to clutch closing position, a latch associated with each of said levers and restraining its inward motion, and a trip for tripping said latch and permitting the quick inward motion of the corresponding lever. 70 75 80 85

2. In a hoisting mechanism, the combination of a driven shaft, a worm carried by said shaft, a worm wheel having a locking engagement with said worm and having an extended shaft, a pair of pinions carried by said worm shaft, a bevel gear meshing with said pinions and rotating such pinions in opposite directions, said bevel gear having a second bevel gear face, a driving pinion meshing with the teeth on the second face of said bevel gear, and interlocking means for closing one or the other of said clutches, and means for selectively locking said pinions to said shaft. 90 95 100

In testimony that I claim the foregoing I have hereunto set my hand at Milwaukee, in the county of Milwaukee and State of Wisconsin. 105

THEODOR ZETTERLUND.
